DESIGN FOR A DRESS

Jacob J. Kushner, New York, N. Y.

Application October 11, 1937, Serial No. 72,114

Term of patent 3½ years

To all whom it may concern:

Be it known that I, Jacob J. Kushner, a citizen of the United States of America, residing in city of New York, county of New York, and State of New York, have invented a new, original, and ornamental Design for a Dress, of which the following is a specification, reference being had to the accompanying drawing, forming part thereof,

Fig. (1) is a front view of a dress showing my new design.

Fig. (2) is a rear view thereof.

The characteristic feature of my design resides in the specific embroidery in combination with the tucking on the waist portion of the dress as shown.

I claim:

The ornamental design for a dress substantially as shown and described.

JACOB J. KUSHNER.
